DESIGN.

A. L. HALLIDAY.

CARPET.

No. 17,973.

Patented Dec. 20, 1887.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,973, dated December 20, 1887.

Application filed September 8, 1887. Serial No. 249,182. Term of patent 3½ years.

To all whom it may concern:

Be it known that I, ARTHUR L. HALLIDAY, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is composed of several figures or groups, which are repeated in succession over the face of the carpet upon any suitable ground.

Figure A is a group of leaves and flowers 20 arranged upon a curving stem, giving the entire group a circular shape, with the central portion somewhat open. At the lower side is a thick cluster of leaves inclosing groups of small star-shaped flower forms, also a stem 25 bearing a number of similar flower forms overlying large leaves. In the upper part of the figure smaller leaves and similar star-shaped flowers are scattered along the main stem.

Here and there in the group are leaves ornamented with open-work.

Figure B consists of a mass of leaves over 30 which lie a number of gem-shaped flowers. Above are larger leaves, and from one side a long slender stem projects, curving around at the top and supporting a large flower at the 35 side and at the top a row of small indented leaves.

Figure C consists of a number of large leaves supported on a stem-work and forming a center, which is partly encircled by gem-shaped 40 flowers. Along the rest of the stem, above and below, are leaves and flowers.

Between the groups small ornamental square 45 figures are scattered irregularly. Some of these small figures are connected with and form part of the large groups. Others are separate and distinct from the groups, occurring in the intervals between them.

What I claim as new, and desire to secure by 50 Letters Patent, is—

The design for carpets, consisting of the design substantially as shown.

ARTHUR L. HALLIDAY.
